(57) **CLAIM**

The ornamental design for a visual dome indicator panel, as shown and described.

DESCRIPTION

U.S. Patent application Ser. No. 12/052,912, filed Mar. 21, 2008.

FIG. 1 is a perspective view of the visual dome indicator panel, showing the new design;

FIG. 2 is a front elevational view thereof;

FIG. 3 is a rear elevational view thereof;

FIG. 4 is a right side view thereof; the left side view being a mirror image;

FIG. 5 is a top plan view thereof; and,

FIG. 6 is a bottom plan view thereof.
